UNITED STATES PATENT OFFICE.

JOHN C. WANDS, OF ST. LOUIS, MISSOURI.

AIR-BRAKE CONTROLLER.

SPECIFICATION forming part of Letters Patent No. 680,091, dated August 6, 1901.

Application filed August 4, 1900. Serial No. 25,914. (No model.)

To all whom it may concern:

Be it known that I, JOHN C. WANDS, a citizen of the United States, residing at St. Louis, in the State of Missouri, have invented certain new and useful Improvements in Air-Brake Controllers; and I hereby declare the following to be a full, clear, and exact description of the same, reference being had to the accompanying drawings, in which—

10 Figure 1 is a top plan view of devices embodying my invention shown in connection with an air-brake cylinder, its piston-rod, portions of the cylinder-levers, and the tie-rod connecting said levers. Fig. 2 is a side elevation of the same, showing the devices as attached to the bottom of a car. Fig. 3 is an enlarged partial view in plan of the left-hand end of Fig. 1, showing the screw-housing, spring-housing, and bracket which supports the same, the latter in transverse section, the section being taken on the line 3 3, Fig. 4. Fig. 4 is an enlarged side view of the left-hand end of the devices as shown in Fig. 1, the bracket and spring-housing being in elevation, the sliding fulcrum-block broken away, and the screw-housing in longitudinal section on the line 4 4, Fig. 1. Fig. 5 is an enlarged partial end view of the devices viewed from the left of Figs. 1 and 2, parts broken away to show the pawl-and-ratchet mechanism for actuating the feed-screw.

15 Like symbols refer to like parts wherever they occur.

My invention relates to that class of devices sometimes termed "slack-adjusters," which have for their function the automatic elimination of slack from brake systems, whether the said slack arises from shoe wear, stretch, or other cause. As is well understood by those skilled in the art, slack or lost motion in a brake system incident to service wear on shoes, &c., and which is practically immaterial in hand-braking, is of vital importance in power-braking, where the slack is multiplied back onto the air-brake piston and may reach such an extent as to exhaust the working stroke of the piston without setting the brakes. This class of devices as heretofore generally constructed depends on using the excessive travel of some portion of the brake system distant from the power devices to actuate mechanism which shall either

shorten up the connections between the levers of the systems or change the relative position of the fulcrums of the levers of the 55 brake-rigging, and such constructions are more or less liable to be rendered inefficient by unequal wear on the brake-shoes and other causes which vary the paths of travel of the pull-rods and the positions of the levers of 60 the brake system, a slight variation of position being in many constructions sufficient to derange the operation of the devices. To overcome the several objections, I combine with the fulcrum of the cylinder-lever mechanism actuated either by the piston-rod or lever connected thereto, whereby any excessive travel of the piston-rod causes such movement of the cylinder-lever fulcrum as shall eliminate the slack from the system at a point 70 adjacent to the power devices, and such a construction embodies the main feature of my invention.

In carrying out my invention I prefer to employ in combination with a cylinder-lever 75 a sliding fulcrum-block, a feed-screw for moving the same, pawl-and-ratchet mechanism for actuating the feed-screw, a connection between the pawl-and-ratchet mechanism and the piston-rod of the air-brake or like power 80 mechanism, and retracting mechanism whereby the adjustment is effected on the release or taking off of the brakes, and the same embodies a secondary feature of my invention.

There are other minor features of invention, all as will hereinafter more fully appear.

I will now proceed to describe my invention more fully, so that others skilled in the art to which it appertains may apply the same.

90 In the drawings, A indicates an air-brake cylinder; a, its piston-rod; B and B', cylinder-levers with which the brake system may be connected in the usual and well-known way, and C the tie-rod connecting the cylinder-levers, one of said levers B being connected with the piston-rod a, which operates the brake system, and the other, B', fulcrumed on the cylinder, the general arrangement chosen for purposes of illustration being substantially that of what is termed "passenger equipment."

100 In carrying out my invention the fulcrum of the cylinder-lever B' is made adjustable

by mechanism interposed between it and the piston-rod a , so as to be actuated by any excessive travel of the piston-rod, and for this purpose I provide what I term a "feed-screw housing" 1, which may be a casting and is adapted to be attached to the cylinder-head a' at one end and may be supported at the other by a bracket 2, which may be attached to the bottom of the car in line with the air-brake cylinder A. The feed-screw housing 1 is slotted below to receive and guide the sliding fulcrum-block 3, its inner and outer ends being tubular to retain and journal the feed-screw which moves the fulcrum-block 3. 15 3 indicates a sliding fulcrum-block, to which one end of the cylinder-lever B' is pivotally connected, said sliding fulcrum-block having a nut or threaded bore, through which the feed-screw 4 passes. Loosely journaled on 20 the outer end of the feed-screw 4 is a hollow pulley or sheave 5, carrying in its interior a pawl 6, adapted to engage a ratchet-wheel 7, attached to the end of the feed-screw within the hollow sheave, whereby the sheave may 25 turn loosely on the feed-screw in one direction, but in its reverse movement causes the feed-screw to turn with it. The projecting end of the feed-screw 4 is provided with an attached sprocket or hand wheel 4 a , and the 30 projecting end of the pawl-shaft is provided with a thumb-piece 6 a , whereby the pawl 6 may be disengaged from the ratchet 7 and the feed-screw turned manually when the sliding fulcrum-block 3 is to be adjusted for 35 the application of new or worn brake-shoes or for like purposes.

8 indicates a spring case or pocket carried by or mounted on the bracket 2, which supports the outer end of the feed-screw housing 1, and said spring-case is preferably arranged parallel with the feed-screw housing and incloses a spring (see dotted lines, Fig. 1) or equivalent means for retracting the bridle or flexible connection between the piston-rod 45 a and sheave 5. Between the sheave 5 and the spring-case 8 the bracket 2 carries a pulley 9, around which the flexible connection or bridle passes, and a pulley 10 for a similar purpose is interposed between the sheave 5 and the piston-rod a .

Arranged parallel with the path of the piston-rod a and at the limit of its normal working travel is a rock-shaft 11, properly supported—as, for instance, from the car-bottom—and said rock-shaft is provided with one arm 11 a , which stands in the path of the piston-rod, and a second arm 11 b , which may have an eye and with which the flexible connection or bridle leading from sheave or pulley 5 is connected, either directly or preferably through an intermediate pull-rod 12, which may pass through a guide 12 a or be otherwise suitably supported against sagging.

13 indicates a bridle or flexible connection 65 between the sheave 5 and the rock-shaft 11, which latter is actuated by the excessive travel of the piston-rod a and in turn actu-

ates the sheave 5 in one direction. The bridle or flexible connection 13 is connected at one end to the arm 11 b of the rock-shaft and after passing over pulley 10 is connected at an intermediate point to the sheave or pulley 5, then passes over pulley 9 on bracket 2 and has its other end connected to the retracting-spring inclosed within the spring-case 8, the length of the several connections 12 and 13 being such that when the rock-shaft 11 is rotated by excessive movement of piston a the sheave 5 will be rotated (and will turn loosely on feed-screw 4) and the spring within the 80 spring-case 8 will be put under sufficient tension to retract the bridle (or connections 12 and 13) and reversely rotate the sheave 5 when the piston a makes its instroke or the brakes are released. 85

The construction and combination of the devices being substantially such as hereinbefore pointed out, they will operate as follows to eliminate slack or lost motion from the brake system: The location of rock-shaft 9c 11 and its arm 11 a being in the path of and at the extreme of the normal outward travel of the piston a and the length of the flexible connections or rod 12 and bridle 13 between the arm 11 b of the rock-shaft 11 and the 95 sheave 5 and between the sheave 5 and the retracting-spring housed in spring-housing 8 being such that when the rock-shaft is actuated by the excessive travel of the piston a the sheave 5 is rotated (loosely) on the feed-screw 4, the pawl 6 sliding over the teeth of ratchet 7, and the retracting-spring in casing 8 being put under tension, (or compression, as the case may be,) it follows that the release of the brakes or inward movement of 105 piston a will permit the operation of the retracting-spring to reversely rotate the sheave 5 and through the ratchet mechanism 6 7 rotate the feed-screw 4, thus causing a movement of the sliding fulcrum-block 3 proportionate to the excessive movement of piston a in its outward stroke. This movement of the fulcrum-block 3 so changes the position of the fulcrum of the cylinder-lever B' as to 110 compensate for any wear or lost motion in 115 the brake system and thereafter reduce the movement of the piston a to its normal travel.

Having thus described my invention, what I claim, and desire to secure by Letters Patent, is—

1. In an air-brake controller, the combination with cylinder-levers and an air-brake piston, of a movable fulcrum for one of the cylinder-levers other than that connected with the piston-rod, means for causing the travel 125 of said movable fulcrum, and a contact connection arranged in the path of the piston-rod for transmitting the excessive travel of the piston to the devices which actuate the movable fulcrum; substantially as and for the 130 purposes specified.

2. In an air-brake controller, the combination with cylinder-levers and an air-brake piston, of a movable fulcrum-block for one of

the cylinder-levers, a feed-screw for actuating the movable fulcrum-block, pawl-and-ratchet mechanism for actuating the feed-screw, and a bridle or flexible connection interposed between the pawl-and-ratchet mechanism and the air-brake piston; substantially as and for the purposes specified.

5 3. In an air-brake controller, the combination with cylinder-levers and an air-brake piston, of a movable fulcrum-block for one of the cylinder-levers, a screw-feed and a pawl-and-ratchet mechanism for actuating the movable fulcrum-block, a bridle or flexible connection between the pawl-and-ratchet mechanism and the air-brake piston, and means for reversely actuating the pawl-and-ratchet mechanism on the instroke of the piston; substantially as and for the purposes specified.

10 4. In an air-brake controller, the combination with cylinder-levers and an air-brake piston, of a feed-screw housing mounted on the head of the air-brake cylinder, a sliding fulcrum-block for one of the cylinder-levers,

15 and a feed-screw carried by the feed-screw housing, a loose sheave, and a pawl-and-ratchet mechanism carried by the feed-screw, a rock-shaft, a retracting-spring, and suitable connections between the rock-shaft, sheave, and retracting-spring; substantially as and for the purposes specified.

20 5. In an air-brake controller, the combination with cylinder-levers and an air-brake piston, of a movable fulcrum-block for one of said levers other than that connected with the piston, a rock-shaft arranged in the path of the piston-rod, and means for actuating the movable fulcrum-block from the rock-shaft, substantially as and for the purposes specified.

25 In testimony whereof I affix my signature, in presence of two witnesses, this 30th day of July, 1900.

JOHN C. WANDS.
